UNITED STATES PATENT OFFICE.

CHARLES B. VAN DYKE, OF MUSKEGON, MICHIGAN.

INDEX.

1,075,522.

Specification of Letters Patent.

Patented Oct. 14, 1913.

Application filed April 1, 1912. Serial No. 637,922.

To all whom it may concern:

Be it known that I, CHARLES B. VAN DYKE, a citizen of the United States, residing at Muskegon, in the county of Muskegon 5 and State of Michigan, have invented new and useful Improvements in Indexes, of which the following is a specification.

My present invention relates to card-indexes, and its object is to provide an improved alphabetical card-index, by which any name or word may be indexed with absolute exactness; which need have no more indexing members than the indexed material at the time requires; and which shall be 10 expansible and contractible to the requirements of any changes in such material. This object is attained by, and the invention finds a preferable embodiment in, the card index hereinafter described and illustrated by the 15 accompanying drawings, in which:—

Figure 1 is a perspective view of my card-index having indexing members sufficient in number and character to illustrate the method and mode of operation of my index, 20 such members being arranged in proper order in a suitable drawer or tray 38; Fig. 2 is a view of an indexing member adapted to be used therein; and Fig. 3 is a front downward view of other such indexing members 25 having various indexing letters, similarly illustrating a form of my index, and being arranged in order in a similar drawer or tray 39.

In my index the indexing members, commonly called "guide cards" are, to distinguish the indexed names appearing on the following cards 40, marked with the letters of the alphabet so positioned thereon, as on their tabs 41 that such distinguishing letter 30 in the first position (as in guide cards 1, 2 and 3 of Fig. 1) indicates the first letter of the name indexed; the distinguishing letter in the second position—immediately to the right of the first position—(as in guide 35 cards 10, 11, 12, 13, 14, 15, 16, 17, 18, 19, 20, 21 and 22 of Fig. 1) indicates the second letter of such name; the distinguishing letter in the third position—immediately to the right of the second position (as in guide 40 cards 30, 31, 32, 33, 34, 35 and 36 of Fig. 1 and 37, Fig. 2) indicates the third letter of such name, and so on. It is contemplated that no more guide cards shall be incorporated into my index than may from time to 45 time, as the indexed material increases, become necessary; and that when any such

guide card becomes no longer necessary by reason of the withdrawal of its indexed material, it may be removed from the index.

It is evident that, by incorporating a sufficient number of guide cards with distinguishing letters in the proper positions thereon, an absolutely exact index for any name or word may be provided; usually, however, it will be found sufficient to incorporate guide cards ranging over perhaps four or five such positions for their distinguishing letters.

In the index shown in Fig. 1, the name "Aachen" will be found immediately after 70 guide card 30; the word "Abacus" immediately after guide card 31; the name "Babel" after guide card 33; the word "Cask" after guide card 21; the word "Bed" after guide card 35, etc. These names being indexed, if 75 it is desired to index the word "Bee," guide-card 37 is inserted after card 35, and after card 37 a card 40 showing such indexed word, etc.

A less number of guide cards may be employed in many cases, without detracting from the absolute exactness of the index, by printing two or more consecutive distinguishing letters on one guide card as shown in guide card 50 in Fig. 3, which may be 80 followed by guide cards 51, 52, 53, 54, 55 and 56, etc., displaying distinguishing letters in the second position, and guide card 57, 58, 59, 60, 61 and 62, etc., having distinguishing letters in the third position, and so on, as 85 illustrated in Fig. 3. Moreover, inasmuch as certain combinations of consecutive letters are never, or practically never, found in words, only such guide cards need be incorporated whose distinguishing letters display 90 those combinations which are practical; thus the letter Q being always followed by the letter U, all the guide cards for words beginning with Q may display also the letter U.

Not confining myself to the details of construction shown and described, I claim:

1. In an expansible and contractible alphabetical index, a series of separable indexing members severally displaying a letter of the indexed words in such conventional position thereon as to indicate the numerical order of such letter in such words.

2. In an expansible and contractible alphabetical index, a series of separable indexing members displaying letters of the indexed words thereon and arranged in sets,

the displayed letters of the first set of such members indicating by their position on said members that such letters are the first letters of the indexed words, the displayed 5 letters' position on the second set being to the right of the displayed letters' position on the first set to indicate that such displayed letters of the second set follow in the indexed words the displayed letters of 10 the first set, the third set's displayed letters' position being to the right of the displayed letters' position on the second set to indicate that such displayed letters on the third set follow in the indexed words the displayed 15 letters of the second set, and so on through the sets of indexing members composing the series, whereby the words may be indexed with absolute exactness.

3. In an expandible and contractible 20 alphabetical index, a series of separable indexing members arranged in sets and displaying letters of the indexed words thereon, some such members displaying combinations of the consecutive letters of the indexed words sufficient to index with absolute 25 accuracy all indexed words therein and ar-

ranged in sets, the displayed letters of the first set of such members indicating by their position on said members that such letters are the first letters of the indexed words, the 30 second set's displayed letters' position on the second set being to the right of the displayed letters' position on the first set to indicate that such displayed letters of the second set follow in the indexed words the 35 displayed letters of the first set, the third set's displayed letters' position being to the right of the displayed letters' position on the second set to indicate that such displayed letters on the third set follow in the indexed 40 words the displayed letters of the second set, and so on through the sets of indexing members composing the series, whereby the words may be indexed with absolute exactness. 45

In testimony whereof I have hereunto set my hand in presence of two subscribing witnesses.

CHARLES B. VAN DYKE.
